DESIGN FOR A WASHBOARD

Maude L. Irwin, Alameda, Calif.

Application July 25, 1938, Serial No. 78,685

Term of patent 14 years

To all whom it may concern:

Be it known that I, Maude L. Irwin, a citizen of the United States and a resident of the city of Alameda, county of Alameda, State of California, have invented a new, original, and ornamental Design for a Washboard, of which the following is a specification, reference being had to the accompanying drawing forming a part thereof.

I claim:

The ornamental design for a washboard, as shown.

MAUDE L. IRWIN.
